CLAIM

The ornamental design for a data card, as shown and described.

DESCRIPTION

FIG. 1 is a front perspective view of a data card showing our new design, on an enlarged scale;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top elevational view thereof; and,

FIG. 7 is a bottom elevational view thereof.

The broken line drawing in FIG. 2 is for illustrative purposes and forms no part of the claimed design.
